UNITED STATES PATENT OFFICE

MARY FORTE, OF NEW YORK, N. Y.

DESIGN FOR A SOUVENIR TOY OR SIMILAR ARTICLE

Application filed July 9, 1932. Serial No. 44,291. Term of patent 3½ years.

To all whom it may concern:

Be it known that I, MARY FORTE, a subject of the King of Italy, residing at New York city, in the county of Westchester and State of New York, have invented a new, original, and ornamental Design for Souvenir Toys or Similar Articles, of which the following is a specification.

Fig. 1 is a side view of a souvenir toy or similar article showing my new design.

Fig. 2 is a perspective view of the same partly in open position.

Fig. 3 is a face view of the same in fully open position.

I claim:

The ornamental design for a souvenir toy or similar article as shown.

In testimony whereof I have affixed my signature.

MARY FORTE.
